UNITED STATES PATENT OFFICE.

ERNEST S. JOHNSON AND ROBERT J. BECKLEY, OF WATERLOO, IOWA.

PERFORATING DEVICE FOR BANK-CHECKS.

1,250,317.

Specification of Letters Patent. Patented Dec. 18, 1917.

Application filed December 30, 1916. Serial No. 139,759.

To all whom it may concern:

Be it known that we, ERNEST S. JOHNSON and ROBERT J. BECKLEY, citizens of the United States of America, and residents of 5 Waterloo, Blackhawk county, Iowa, have invented certain new and useful Improvements in Perforating Devices for Bank-Checks, of which the following is a specification.

10 Our invention relates to improvements in protective devices for checks and the like, and the object of our improvement is to supply a foldable check-case with a check-punch mounted thereon conveniently and 15 permanently, said punch having thereon counterpart fastening-means for an overlapped part of the case.

This object we have accomplished by the means which are hereinafter described and 20 claimed, and which are illustrated in the accompanying drawings, in which Figure 1 is a perspective view of a foldable case containing a pad or book of checks, with our improved punch and case-fastening 25 means mounted thereon; Fig. 2 is an enlarged side elevation of the check-punch and a part of the check-case on which it is mounted, parts of the punch being shown in section; Fig. 3 is a plan view of the 30 spring-plate part of said punch before bending, and Fig. 4 is a plan view of a part of a bank-check, showing thereon the impression of said punch as used to designate and obliterate a definite limiting numeral designating a value not exceeded by 35 the actual face value of the check.

Similar numerals of reference denote corresponding parts throughout the several views.

40 The casing 7 is of a well-known foldable kind provided with an interior pocket 12 adapted to receive a part of the backing board of a pad or book of blank checks 11. This case has a flap 10 adapted to fold and 45 be overlapped upon an underlying part.

Upon said underlying part of the case is secured a check-punch by means of a headed rivet 8, the head of the rivet adapted for detachable fastening engagement with a 50 socket 9 mounted in the flap 10. The punch consists of a plate-spring 1 doubled upon itself medially to provide two superposed members which are connected by means of said rivet 8 passed through holes 2. Said 55 members are provided near their free ex-

tremities with die-like faces 6 and with counterpart punching-means consisting of punches 4 in one member receivable into slots 5 in the other member. These punches and die-faces may be of any desired forms 60 and numbers, but as shown, the dies consist of knurled spaces located between pairs of the said punches 4 and the pairs of slots 5. The punches and slots are straight but may be curved or circular if desired, and 65 the cutters 4 are produced by cutting them at 3 from the body of said plate 1. The punch is especially adapted to be employed upon a bank-check 11 or any other document on which a face-value is indicated, 70 and where a plurality of consecutive or differing limiting numerals 13 are placed in an increasing series.

The punch is then operated to cut and impress one of said limiting numerals 13 75 as shown at 14 and 15, the numeral 14 indicating the incisions made by the cutters 4 while the material of the check is roughened at 15 between said incisions by the die-faces 6, thus indelibly effacing or impressing 80 one of said numerals, the effaced numeral indicating the value next above the face value of the check.

Having described our invention, what we claim as new, and desire to secure by Letters Patent, is:

1. A check protecting device, consisting of a spring-plate doubled to form overlapping members, one of said members having a pair of transverse slots and the other 90 member having a pair of blades partially cut out and bent over to be receivable through said slots, and the opposed surfaces of said members between said tongues and said slots respectively having rugose mating 95 die faces.

2. A check protector, consisting of a spring-plate doubled upon itself to form overlapping members, a supporting body, means for medially connecting said members together and to said supporting body, and mating dies on opposed faces of the extremities of said members. 100

Signed at Waterloo, Iowa, this 12th day of Dec. 1916.

ERNEST S. JOHNSON.
ROBERT J. BECKLEY.
